BEAM HANGER

Walter W. Erlewine, Long Beach, Calif.

Application July 26, 1935, Serial No. 33,211

10 Claims. (Cl. 74—41)

This invention relates to a beam hanger whereby the operating end of the beam is coupled to the polished rod for the purpose of pumping a well.

5 An object of my invention is to provide a beam hanger which has a straight lift and in which the reins are coupled to the head by a universal connection.

Another object is to provide a beam hanger of 10 the character stated, in which the head is attached to the blocks on the beam in a simple and novel manner.

15 A feature of my invention resides in the novel universal joint in the lower end of the head, so that a straight lift is accomplished, and further in the novel back brace which is attached to the head, and thirdly, the novel oiling arrangement for the universal coupling.

Other objects, advantages and features of invention 20 may appear from the accompanying drawing, the subjoined detailed description and the appended claims.

In the drawings:

25 Figure 1 is a side elevation of my hanger as mounted on a beam.

Figure 2 is a front elevation of the hanger, the lower portion of which is broken away to show interior construction.

30 Figure 3 is a side elevation of my hanger, the lower portion of which is broken away to show interior construction.

Figure 4 is a fragmentary perspective view of the lower part of the hanger head.

35 Figure 5 is a top plan view of the trunnion bearing base.

Figure 6 is a side elevation of the same.

Figure 7 is a perspective view of the trunnion bearing cover.

40 Figure 8 is a perspective view of the bearing liner.

Figure 9 is a top plan view of the same.

Figure 10 is a longitudinal, sectional view of the back brace mounting.

45 Figure 11 is a perspective view of one of the locking collars.

Referring more particularly to the drawings, the beam hanger 1 is supported from one end of the usual beam 2. The hanger includes a head 3 which is preferably supported on the beam 2 in the following manner: A shaft 4 extends through an eye 5 adjacent the upper end of the head. A pair of blocks 6—6 are fixedly mounted on the top of the beam 2 and are slotted to receive the shaft 4.

55 The shaft 4 is held against upward movement

by a pair of collars 7—7 which set over the outer ends of the shaft 4. Each collar is provided with an outwardly extending arcuate lip 8. This lip fits under a lug 9 which projects outwardly from each of the blocks 6. Thus it will be evident that the shaft 4 will be held in the blocks when the collars 7—7 are fitted on the shaft and engage the lugs 9 on the blocks.

On the lower end of the head 3, I provide a shell 10 which is preferably integrally formed 10 with the head. The shell 10 is formed with an arcuate bearing groove 11 in the bottom thereof.

A trunnion bearing base 12 fits in the shell 10, and this base is provided with an arcuate bearing shoe 13 on the bottom thereof. The shoe 13 fits 15 in the groove 11 and thus a rocking motion is permitted in the plane of the horizontal axis of the shell 10.

To prevent the bearing base 12 from moving out of the shell 10, I provide a pair of outwardly 20 extending pins 14—14 on the trunnion base. These pins extend into recesses 15 in the shell, thereby preventing the bearing base from accidentally moving out of the shell when a load is applied to the beam hanger.

25 A metal liner 16 fits in the bearing base 12. The liner is provided with oil grooves 17 and holes 18 in the bottom thereof. The holes 18 permit oil to flow downwardly through the liner and onto the inner face of the bearing base 12.

30 A cap 19 is bolted on to the base 12, so as to enclose the trunnion 20. The outer ends of the trunnion 20 are hexagonal in shape and receive reins 21—21. The reins extend downwardly to the usual polished rod clamp, all of which is usual 35 and well known in the art. The central portion of the trunnion 20 is enlarged as shown in Figure 2, and when the cap 19 is bolted in position, the trunnion is held against endwise movement.

35 A tongue 22 is provided in the liner 16, and this 40 tongue extends into an angular groove in the trunnion, thus further aligning the trunnion in the bearing base.

45 A back brace 23 is pivotally attached to ears 24 of the head, and this back brace is fixedly 45 attached to a bracket 25, which is secured to the beam 2.

50 A pair of hemispherical thrust buttons 26 screw onto the back brace 23, and these buttons bear against the front and rear faces respectively, of the bracket 25. The hemispherical shape of the buttons 26 permits the back brace 23 to extend in various vertical angles from the bracket 25 to the head 3, that is, this particular 55

construction permits the back brace to be angularly adjusted to suit various conditions.

Having described my invention, I claim:

1. A beam hanger comprising a head, mounting means for the head on a beam, a universal joint at the lower end of the head, a pair of reins, means on the universal joint to which the reins are attached, a back brace pivotally attached to the head, a bracket attached to the beam and a pair of hemispherical buttons threaded onto the back brace, said buttons engaging front and rear faces of the bracket.

2. A beam hanger comprising a head, a shaft mounted in the head adjacent the upper end thereof, block mounted on the top of the beam, said shaft being seated in the block, a collar fitted over each end of the shaft, a lip on each of the collars, outwardly extending lugs on the block, said lip extending under the lugs whereby the shaft is held in the block, and reins attached to the head.

3. A beam hanger comprising a head, a shaft mounted in the head adjacent the upper end thereof, a block mounted on the top of the beam, said shaft being seated in the block, a collar fitted over each end of the shaft, a lip on each of the collars, outwardly extending lugs on the block, said lip extending under the lugs whereby the shaft is held in the block, a universal joint in the lower end of the head, a pair of reins and means on the universal joint to which said reins are attached.

4. A beam hanger comprising a head, a shaft mounted in the head adjacent the upper end thereof, a block mounted on the top of the beam, said shaft being seated in the block, a collar fitted over each end of the shaft, a lip on each of the collars, outwardly extending lugs on the block, said lip extending under the lugs whereby the shaft is held in the block, reins attached to the head, a back brace pivotally attached to the head, a bracket secured to the beam, a pair of hemispherical buttons threaded onto the back brace, said buttons engaging the front and rear faces of the bracket.

5. A beam hanger comprising a head, means pivotally mounting the head on the beam, a cylindrical shell on the lower end of the head, a trunnion bearing base journaled in the shell, a trunnion mounted in said bearing base, a pair of reins attached to the trunnion, a cap removably attached to the bearing base and a liner removably mounted in the bearing base, said trunnion resting on the liner.

55 6. A beam hanger comprising a head, means pivotally mounting the head on the beam, a cy-

lindrical shell on the lower end of the head, a trunnion bearing base journaled in the shell, a trunnion mounted in said bearing base, a pair of reins attached to the trunnion, a pair of horizontally extending pins projecting from the bearing base, said shell having recesses formed therein adapted to receive said pins.

7. A beam hanger comprising a head, means pivotally mounting the head on a beam, a cylindrical shell on the lower end of the head, said shell having an arcuate bearing groove in the bottom thereof, a trunnion bearing base, an arcuate shoe on the base, said shoe being fitted in said groove, a trunnion journaled in the bearing base and a pair of reins mounted on the outer ends of the trunnion.

8. A beam hanger comprising a head, means pivotally mounting the head on a beam, a cylindrical shell on the lower end of the head, said shell having an arcuate bearing groove in the bottom thereof, a trunnion bearing base, an arcuate shoe on the base, said shoe being fitted in said groove, a trunnion journaled in the bearing base, a pair of reins mounted on the outer ends of the trunnion, a cap detachably secured to the bearing base and a liner in the bearing base, said trunnion resting on the liner.

9. A beam hanger comprising a head, means pivotally mounting the head on a beam, a cylindrical shell on the lower end of the head, said shell having an arcuate bearing groove in the bottom thereof, a trunnion bearing base, an arcuate shoe on the base, said shoe being fitted in said groove, a trunnion journaled in the bearing base, a pair of reins mounted on the outer ends of the trunnion, a pair of pins extending from the bearing base, said shell having recesses therein adapted to receive said pins and a cap detachably secured to the bearing base.

10. A beam hanger comprising a head, means pivotally mounting the head on a beam, a cylindrical shell on the lower end of the head, said shell having an arcuate bearing groove in the bottom thereof, a trunnion bearing base, an arcuate shoe on the base, said shoe being fitted in said groove, a trunnion journaled in the bearing base, a pair of reins mounted on the outer ends of the trunnion, a pair of pins extending from the bearing base, said shell having recesses therein adapted to receive said pins, a cap detachably secured to the bearing base, a back brace pivotally attached to the head, a bracket secured to the beam, a pair of hemispherical buttons screwed onto the back brace, said buttons bearing against the front and rear faces of the bracket.

WALTER W. ERLEWINE.
